PLASTIC SHEET FOLDING MACHINE

Ralph F. Taber, Buffalo, N. Y.

Application February 6, 1947, Serial No. 726,918

17 Claims. (Cl. 18—19)

1

This invention relates to a machine for forming folds in plastic sheets.

The invention comprehends a machine for folding sheet material provided with a heated folding blade mounted for reciprocating movement to and from a position where it operates in cooperation with a co-acting fold forming means to permanently form a fold through the timed operation of the heated folding blade engaging and folding the sheet in the fold forming means where it is adapted to be retained until the fold is permanently set in the sheet material.

The invention provides a machine for rapidly folding plastic sheet material having a heated folding blade movable toward and from a folding position where a sheet to be folded is supported on a pair of fold forming bars, at least one of which is relatively movable to the other in a direction substantially perpendicular to the movement of the folding blade. The folding blade is moved to engage a sheet to be folded between the fold forming bars in spaced apart position. The folding blade is then moved slowly between the separated fold forming bars to bend the sheet while it is heated. As the sheet is softened by the heat at the corners of the blade, the fold is formed around the end of the blade. The bars are held in the same spaced position while the folding blade moves to its full folding position therebetween. The sheet does not engage the sides of the folding blade, only the corners at the free edge. The blade is then withdrawn from the fold portion, the sheet being retained between the bars which are then moved closer together to bend the fold portion of the sheet to bring the sheet portions at opposite sides of the fold into close contact while cooling the heated portions of the sheet so that a permanent complete fold will be formed. When the fold portion of the sheet has cooled and set, the bars are moved apart to their initial position to discharge the folded sheet.

The invention further comprehends a machine for folding plastic material having a reciprocating folding blade movable to and from a fold forming position in cooperation with a pair of fold forming bars movable toward and from each other in timed relation with the folding blade; a machine having a frame provided with pivoted arms carrying the folding blade for its reciprocating movement relative to the forming bars, a top portion on the frame for supporting sheet material to be folded between the folding blade and forming bars, and a carrier pivoted on the frame and having a top portion carrying one of the forming

2

bars for movement relative to the other forming bar mounted in opposed relation thereto on the frame; a machine wherein the forming bars may have the movement of the one mounted on the carrier relative to the other forming bar varied relative to the movement of the folding blade for varying the folding cooperation obtained between the blade and the forming bars; a machine having the folding blade mounted on the frame for reciprocating movement and arranged for adjustment on the frame relative to the forming bars carried thereby so that the fold forming portion of the folding blade may be adjusted into centered position between the spaced parallel forming bars in each adjusted position of operation thereof; a machine wherein the forming bars are provided with resilient sheet engaging strips on the opposed faces thereof for cooperation in folding and retaining the sheet between the forming bars while the folding blade is withdrawn from the fold portion therein, and to further hold the portions of the sheet at opposite sides of the fold closely together while the forming bars and resilient strips absorb the heat transmitted to the sheet by the folding blade for cooling and setting the fold in the sheet; a sheet folding machine wherein an operating lever is provided for oscillating movement from and to a starting position for moving the folding blade and forming bars to engage and fold a sheet between said bars; a sheet folding machine having means controlling the movement of the folding blade and forming bars relative to each other so the movement of the folding blade is at a substantially slow rate as the blade engages and folds a sheet between the forming bars; a machine wherein suitable means is provided for returning and timing the return movement of the operating lever to the starting position to secure a slow withdrawal of the folding blade from the fold portion in the sheet with the retention of the sheet between the forming bars for a period of time after the folding blade has been withdrawn, to tightly fold the sheet and absorb the heat in the fold portion; and to provide means for encasing the heated folding blade structure in a manner that will provide effective protection of the heated folding blade for reducing the likelihood of injury to an operator of the machine.

In the drawings:

Fig. 1 shows the folding machine constructed according to the invention in side elevation, looking at the right-hand side, with the major portion of the right-hand side cover broken away to show details of construction.

Fig. 2 is a view similar to Fig. 1, showing the

left-hand side of the folding machine in side elevation, with the major portion of the left-hand side cover broken away.

Fig. 3 is a horizontal cross-section taken substantially on the line 3—3 of Fig. 2.

Fig. 4 is a horizontal cross-section taken substantially on the line 4—4 of Fig. 2.

Fig. 5 is an enlarged fragmentary cross-section taken substantially on the line 5—5 of Fig. 1 showing the details of construction of the carrier 10 operating cam mechanism.

Fig. 6 is an enlarged fragmentary vertical cross-section taken on line 6—6 of Fig. 3.

Fig. 7 is a wiring diagram showing the circuit connections for the folding blade heater and 15 thermostatic control.

Fig. 8 is an enlarged diagrammatic cross-section illustrating the position of the folding blade and forming bars at the beginning of a sheet folding operation with the edge of the folding blade 20 engaged with a sheet to be folded.

Fig. 9 shows the movement of the folding blade from the position of Fig. 8 in folding the sheet between the forming bars with the folding blade in the full folding position between the bars.

Fig. 10 shows how the sheet is held between the forming bars by the resilient strip members as the folding blade is withdrawn from its maximum fold forming position shown in Fig. 9.

Fig. 11 shows the position of the folding blade after it is withdrawn to a further extent from the fold and the sheet engaged and held between the forming bars, together with a showing of the forming bars moved closer together to engage the fold portion and bend it to hold the portions of the sheet at opposite sides of the fold closely engaged during the period when the forming bars absorb the heat from the sheet material and the fold in the sheet takes its permanent set.

Fig. 12 shows an edge view of a sheet completely folded in the manner illustrated in the enlarged diagrammatic cross-sections in Figs. 8 to 11 inclusive.

The improved sheet folding machine is particularly adapted for folding plastic sheet material, such as Celluloid, and has a base 1 provided with side members 2, a rear wall 3, while shoes 4 mounted on the lower ends of side members 2 rest on a floor in supporting the machine.

A rigid supporting frame 5 is mounted on the upper end of base 1 and rigidly secured to the side members 2 and rear wall 3 to form a rigid structure. Supporting frame 5 has spaced substantially parallel side walls 6 depending from the sides of a flat sheet supporting top portion 7. Flat top portion 7 is formed with a centrally located channel 8 extending from the front to the rear portion thereof for receiving the guiding and retaining mechanism carried by gauge bar 9 so constructed that gauge bar 9 may be adjusted with respect to the folding mechanism herein-after described for gauging the distance between one edge of a sheet to be folded and the fold portion to be formed therein.

The front edge of top portion 7 and side walls 6 terminate rearwardly of the bottom front portion of supporting frame 5 and a depending front wall portion 10, see Figs. 1, 2 and 6, extends downwardly from top portion 7 between side walls 6. Front wall portion 10 merges into a downwardly and forwardly inclined front wall portion 11. The lower front portion of front wall portion 11 is formed to merge with a horizontal wall portion 12 spaced above the bottom of supporting frame 5, as shown in Figs. 1, 2 and 6. Horizontal wall 75 of carrier 18, carries stud 28 and roller 25, as

portion 12 extends forwardly to the front of the frame. This formation of front wall portions 10, 11 and 12 provides a chamber at the front of the supporting frame below top portion 7 into which folded sheets may be discharged and guided to the front of the machine where the operator can remove them. A guide plate 13 formed to fit wall portions 10, 11 and 12 is mounted against the front faces thereof, as shown in Fig. 1, and has an upwardly inclined lip on the forward edge to facilitate the guiding and removal of a folded sheet from the frame.

The front margin of top portion 7 and the upper margin of front wall portion 10 are formed to provide a seat 14 for mounting one of a pair of fold forming bars 15 rigidly secured in the seat by means of bolts or the like, as shown in Fig. 6. The other fold forming bar 15 is mounted in a seat 16 formed in top wall portion 17 of a carrier 18. Side extensions 19 on the carrier depend from the sides of top wall portion 17 beyond the outer faces of side walls 6 of frame 5 and are rotatably mounted on transverse shaft 20 having opposite ends extending through side walls 6 in 25 which the shaft is suitably secured. Suitable bolts or the like, as shown in Fig. 6, rigidly secure the other fold forming bar 15 in seat 16.

Top wall portion 17 of carrier 18 is formed to lie in the same horizontal plane as top wall portion 7 30 of frame 5 to provide a flat top surface for supporting a sheet to be folded with the rear edge against gauge bar 9 to gauge the position of the fold in the sheet. Each fold forming bar 15 has the face thereof opposed to the other bar formed 35 with a channel 21 having an angular bottom wall formation, as shown in Fig. 8, for example, to receive a resilient strip member 22, in the manner shown in Fig. 8. Each resilient strip member has one margin seated in the upper portion of the 40 channel against one angular face of the bottom portion of the channel, while the other margin of the strip is engaged in the channel with an inner portion extending inwardly beyond the adjacent face of forming bar 15, as illustrated in Fig. 8. 45 The inner portion of the lower margin of each strip 22 is spaced from the angular bottom portion, as illustrated. These resilient strip members 22, one on each fold forming bar 15, are arranged on the opposed faces of bars 15, as shown 50 in Fig. 8, to provide gripping members arranged so the lower margins of the strip members 22 will grip the outer faces of a folded sheet therebetween, in the manner shown in Figs. 9 to 11 inclusive, and retain the folded sheet between the fold 55 forming bars. These strip members 22 resiliently grip a folded sheet in a manner sufficient to hold the sheet while the folding blade is disengaged from the fold therein. By having the margin of each strip member 22 which engages a folded sheet, spaced from the angular bottom portion of channel 21, it will be understood that in addition to the strips being flexible, they are flexible in the channel relative to bars 15. The upper marginal portions of each strip 22 are rigidly secured in 60 channel 21, as shown.

A cam shaft 23 is rotatably mounted in bearings in side walls 6, projects through the supporting frame with opposite ends projecting beyond the opposite side walls of the frame. A cam 24 65 is rigidly mounted on the right-hand end of cam shaft 23 and has a roller 25 carried by stud 26 engaged with the periphery thereof. Stud 26 rotatably mounts roller 25 on a rearwardly extending portion of right-hand side extension 19 70 of carrier 18, carries stud 28 and roller 25, as

shown in Fig. 1. A disc 27, Fig. 5, is formed with an eccentric opening to receive stud 26. The disc provides an adjustment for the position of roller 25 relative to side extension 19 for adjusting the timed relation of operation and the spaced relation in operation, of fold forming bar 15 mounted on the carrier relative to bar 15 mounted on the frame. Disc 27 is normally retained in adjusted position by tightening a nut 29 on the stud 26, Fig. 5, to clamp the pair of washers 28 against opposite sides of extension 19. A tension spring 30 has one end secured to side extension 19 on the right side of the carrier, as shown in Fig. 1, and the opposite end secured to a pin mounted on right-hand side wall 6 of frame 5. Spring 30 normally holds follower roller 25 engaged with the periphery of cam 24 in order to rock carrier 18 with its forming bar 15 relative to the forming bar carried by the frame.

The opposite end of cam shaft 23 has a ratchet wheel 31 rigidly mounted thereon, as shown in Fig. 2. A pair of plates 32 each have one end rotatably mounted on cam shaft 23 for independent operation relative to one another between ratchet wheel 31 and left-hand side wall 6. Spring-pressed pawls 33 are pivotally mounted on the outer ends of plates 32. Pawls 33 are normally held in engagement with the periphery of ratchet wheel 31 by means of the springs on pawls 33 and plates 32.

An arm supporting shaft 34 is mounted in transversely extending relation in frame 5 at the upper rear portion thereof, as shown for example, in Figs. 1 and 2, with opposite ends extending through side walls 6 and carrying blade supporting arms 35 on the free ends thereof adjacent the outer faces of side walls 6 for pivotal movement relative thereto on eccentrically mounted bearings 36. The inner bearing member has an eccentric mounting on the end of shaft 34, while the outer bearing member is mounted in the free end of blade supporting arm 35, as shown in Fig. 2 for example. The opposite ends of blade supporting arms 35 extend forwardly and upwardly to the front portion of the machine above top portion 7 where they carry the folding blade assembly 37.

The folding blade assembly 37 includes a body member 38 extending between and having opposite ends secured to the free front ends of arms 35. The lower edge of body 38 is provided with a seat for detachably receiving and mounting one margin of folding blade 39 while the opposite margin depends below body 38 and provides a free margin adapted for sheet folding cooperation with fold forming bars 15. A heating element 40 is mounted in body 38 of the folding blade assembly in any suitable manner. Heating element 40 is a conventional form of electric heater adapted for connection in circuit with a source of electric current supply in a manner that will be hereinafter described. Heat indicator 41 is mounted on the blade supporting arm on the left-hand side of the machine and has a portion thereof projecting into body 38 for registering the heat therein. A thermostat control of conventional type is shown at 42 mounted in the right-hand end of folding blade assembly 37, as clearly shown in Fig. 3. This thermostat control is connected in the electric circuit to heating element 40, is responsive to the temperature of the body 38 so as to control the electric circuit for the heating element in a manner well-known in the art to maintain body 38 at a desired temperature according to the adjustment of the thermostat control.

The operating mechanism for reciprocating the folding blade and fold forming bars has an operating shaft 43 rotatably mounted in suitable bearings in side walls 6 and is located in the front portion of rigid supporting frame 5, as clearly shown in Figs. 1, 4 and 6. The bearings for shaft 43 mounted in side walls 6 are indicated at 44, Fig. 4. The ends of operating shaft 43 project outwardly beyond side walls 6. The left-hand end of operating shaft 43 carries an actuating lever 45 and the right-hand end carries an actuating lever 46, as shown in Figs. 1, 2 and 6. Actuating lever 45 has a forwardly extending arm 47 and actuating lever 46 has a similar construction to provide a pivot connection for mounting one end of each of a pair of links 48 on levers 45 and 46, respectively. The opposite ends of links 48 are pivotally connected to the upper free end portions of blade supporting arms 35, as indicated at 49. The undersides of arm 47 and lever 46 near the forward end, carry set screws 50 adjustably mounted therein for engagement with the horizontal top portion of side members 2 for limiting the rocking movement of levers 45 and 46. A pair of links 51 are pivoted to the rear end of actuating lever 45, as shown in Fig. 2 and at the opposite ends are each pivotally connected to the free end of one of the plates 32 so as to connect actuating lever 45 with both plates 32 in order to simultaneously operate spring-pressed pawls 33. A set screw 52 is threaded in the lower rear end portion of actuating lever 45 to engage the top portion of side member 2 for limiting the stroke of movement of actuating lever 45 in a counter-clockwise direction, as shown in Fig. 2. This limits the stroke of movement of spring-pressed pawls 33 with set screw 50 and also determines the stroke of movement of blade 39.

An operating lever 53 has one end mounted on the central portion of operating shaft 43, while the other end extends downwardly to the lower front portion of the base structure where foot pedals 54 are mounted thereon in laterally extending relation. The upper end portion of operating lever 53 has a laterally extending projection 55 receiving one end of a rod 56 mounted therein and extending rearwardly therefrom. The opposite end of rod 56 mounts a weight 57. Weight 57 is detachably secured to rod 56 in any suitable manner and carries a pin 58, as shown in Fig. 4, detachably mounting the free end of piston rod 59 of a dash pot mechanism. Piston rod 59 is slidably mounted and carries a piston in a cylinder 60. The lower end of cylinder 60 is pivotally secured at 61 to a bracket 62 mounted on rear wall 3 of the base.

A suitable guard structure is provided to enclose and protect the folding blade assembly 37, as generally indicated at 63. This guard structure includes an inverted, substantially U-shaped casing 64 enclosing the folding blade assembly and extending transversely across the machine above the front portion of top portion 7, as shown in Figs. 3 and 6. Rearwardly extending casing portions 65 are rigidly secured to opposite ends of and support casing 64. Casing portions 65 have the lower edges mounted on the upper side edge portion of sheet supporting top portion 7 and each has an outwardly extending flange on the upper curved edge portion thereof.

Side covers 66 are hinged along the rear edges to the rear side portions of supporting frame 5 and are shaped to enclose the mechanism at the sides of frame 5 and to cooperate with the ends

of casing 64 and rearwardly extending casing portions 65 to provide a complete enclosure for this operating mechanism, the ends of the folding blade assembly and arms 35 in a manner that will be apparent from the showing in Figs. 1, 2, 3 and 4.

The lower front portion of frame 5 is formed in the central portion to provide a switch box 70, Fig. 4. A cable 71 carries the wires from switch box 70 to heating element 40 and thermostat control unit 42, while cable 72 carries wires from switch box 70 to a connector socket 73 for receiving a plug connection from a source of electric current supply. A switch plate 74 is mounted over the front open end of switch box 70 and carries control switch 75 and pilot lights 76 and 77. Pilot light 76 is connected in the current supply circuit for heating element 40 and is controlled by switch 75, so that whenever switch 75 is closed to connect the heating element 40 in circuit, pilot light 76 will be lighted indicating that the circuit is closed. Pilot light 77 is connected in series with thermostat control 42 for indicating when the thermostat is closed for closing the circuit to heating element 40. Thermostat control 42 also has a series connection in the current supply circuit with heating element 40 in order that the current supply will be interrupted by the operation of the thermostat control whenever the heat in the folding blade assembly reaches the desired temperature. Pilot light 76 goes on and off, indicating when thermostat control 42 is operated to close the circuit to heating element 40 and when the circuit is open.

A condenser 78 is connected in circuit in parallel with thermostat control element 42, as illustrated in Fig. 7, for reducing arcing across the contacts of the thermostat control element when the circuit is broken in a manner well-known in the art.

Figs. 1 to 4 show the machine in the starting position ready to begin a folding operation. With the electric circuits in the machine connected to a source of current supply, the operator operates control switch 75 to close the circuit to the heating element. This is indicated by pilot light 76 becoming illuminated. In starting the machine, heating element 40 will be cool and therefore the thermostat control 42 will close the circuit to heating element 40, in view of which pilot light 77 will also be illuminated. The operator allows the current to heat the folding blade assembly for a sufficient length of time until pilot light 77 goes out, indicating that the heat of the folding blade is at the proper temperature for folding.

The operator sets the gauge bar 9 to the proper position and then feeds a sheet from the front of the machine so that the rear edge will engage gauge bar 9. Then the operator places a foot on one of foot pedals 54 and moves operating lever 53 rearwardly until set screws 50 engage the frame and limit further movement. In the starting position, fold forming bars 15 are spaced apart, as shown in Fig. 8, with the left-hand bar in dot-and-dash line position. Cam 24 is in the position shown in Fig. 1 where one of the dwells 78 is engaged with roller 25.

As soon as the operator begins movement of lever 53 toward the rear wall 3, upward movement of the rearwardly extending end of actuating lever 45, as shown in Fig. 2, will move links 51 upwardly and actuate pawls 33. In this move-

ment, the left-hand pawl 33, as shown in Fig. 2, will engage one of the teeth on ratchet wheel 31 and rotate cam shaft 23 and cam 24 to move the dwell 78 out of engagement with follower roller 25 and bring one of the four intermediate peripheral cam portions 79 into engagement with follower roller 25. At the same time, links 48 operate blade supporting arms 35 to move folding blade 39 downwardly until the free edge engages the upper surface of the sheet to be folded, as shown in Fig. 8. This occurs just prior to the operating lever reaching the rear limit of its stroke of movement and just before set screws 50 engage the frame.

In the meantime, carrier 18 has been operated to move folding bar 15 thereon inwardly to the full line position shown in Figs. 8 and 9, due to intermediate peripheral cam portion 79 engaging follower roller 25. Cam portion 79 is concentric to the axis of shaft 23, as shown in Fig. 1. The heated blade has a square free edge to engage and heats the sheet material at the fold as it moves from the position shown in Fig. 8 to that shown in Fig. 9 so that, with plastic sheet material, the substance from which it is made will be heated at the corners along opposite sides of the folding blade to a softened condition sufficient for the material to bend freely without creating internal stress. The curved sheet portion will bend under tension in spaced relation to the free edge of the folding blade, as shown in Fig. 9.

The sheet being folded will have the portions at opposite sides of the fold extend upwardly along the upwardly and outwardly inclined portions of strips 22 and the upper edges of bars 15, as shown in Fig. 9. These portions of the sheet above the fold will not engage the sides of the folding blade above the lower corners. The position of the parts shown in Fig. 9 is obtained when operating lever 53 has been moved to the rear limit of movement with set screws 50 engaged with the frame. This position of the folding blade may be changed by adjusting set screws 50.

Then, the operator removes his foot from operating lever 53 and weight 57 operates to return the operating lever to the starting position shown in Fig. 1. The speed of return movement of lever 53 is retarded by the operation of the piston in cylinder 60 by controlling the air discharge vent 81 at the bottom of the cylinder. During this return movement actuating lever 45 has a counter-clockwise rotation, as shown in Fig. 2, in which the rear end moves downwardly drawing links 51 downwardly with it. This causes spring pressed pawl 33 on the right-hand side of ratchet wheel 31, as shown in Fig. 2, to engage one of the teeth on the ratchet wheel and continue rotation of the ratchet wheel in a clockwise direction, as shown in Fig. 2. This continues rotation of cam 24 in a counter-clockwise direction, as shown in Fig. 1. In the initial part of the return movement of operating lever 53, folding blade 39 will be moved, as shown in Fig. 10, out of the fold in the sheet which is held by resilient strip members 22 in position between fold forming bars 15. Fold forming bars 15 are retained in the same spaced position shown in Fig. 9 in providing the holding action on the folded sheet while the folding blade is withdrawn.

Then, as operating lever 53 moves an additional distance forward toward the starting position, folding blade 39 moves upwardly into disengaged relation from the fold and from be-

tween bars 15, as shown in full lines in Fig. 11 and then farther up to the position shown in dot-and-dash lines in Fig. 11. When folding blade 39 reaches the full line position shown in Fig. 11, cam 24 is rotated to bring cam lobe 80 into engagement with follower roller 25 and move carrier 19 to bring forming bar 15 carried thereby, still closer to the other forming bar as shown in Fig. 11. The portion of fold forming bars 15 below strips 22 will bend the curved fold portion in the sheet to a greater extent to bring the portions of the sheet at opposite sides of the fold together in close contacting relation. Fold forming bars 15 will simultaneously absorb the heat from the fold portion of the sheet. In this way, the sheet will be rapidly cooled so that the plastic material will set in the folded position and hold the sheet portions on opposite sides of the fold in close surface contact with one another.

Then, as operating lever 53 reaches the forward position, shown in Fig. 1, where set screw 52 engages the frame to limit the forward movement of the operating lever, carrier 18 with its folding bar will be moved into the dot-and-dash line position, shown in Fig. 11, by reason of cam 24 being rotated so that the next dwell 78 therein will receive roller 25. The folding blade will be at its upper limit of movement, as shown in Fig. 1 and set screw 52, as shown in Fig. 2, will engage the frame and limit further forward movement of operating lever 53. When this point is reached, the folded sheet between bars 15 will drop through between the bars down the inclined front portion of the frame against guide plate 13 where it will slide forwardly to the front edge of the guide plate for removal by the operator.

This operation of the machine is such as to produce contact of folding blade 39 with the sheet to soften the material in the portion to be folded, while the blade moves rather slowly in folding the sheet between forming bars 15, in the manner clearly shown in Figs. 8 to 11 inclusive. Sufficient time is provided for engagement of folding blade 39 with the sheet so that a complete fold is formed after which the sheet is held by the folding bars during the dissipation of the heat therefrom. The sheet is then discharged and will have an edge view in elevation, as shown in Fig. 12, for example.

The invention claimed is:

1. A plastic sheet folding machine, comprising a support, a heated folding blade, a pair of fold forming bars mounted for movement of at least one toward and from the other on said support, arm means pivoted on said support and carrying said folding blade for movement toward and from said bars in a direction substantially perpendicular to the plane of movement of said one bar, an operating lever mounted at one end on said support for oscillating movement, an actuating lever connected with said operating lever for oscillation thereby, a link connecting said actuating lever and said arm means for moving said folding blade into cooperative sheet folding relation with said bars in movement of said operating and actuating levers in one direction and away from said bars in movement of said levers in the opposite direction, means operated by said actuating lever for moving said movable fold forming bar a limited distance toward said other bar when said actuating lever is moved in one direction to move said folding blade toward said bars to engage a sheet therebetween for cooperation in initially folding said sheet, said means for moving said movable bar an additional distance toward said other bar in movement of said actuating member in said opposite direction for tightly folding said sheet between said bars while said folding blade is disengaged from the fold in said sheet and moved away from said bars, and means for retarding the speed of movement of said folding blade and actuating lever in said opposite direction for slowly withdrawing said folding blade from the fold in said sheet.

2. A plastic sheet folding machine, comprising a support, a heated folding blade, a pair of fold forming bars mounted for movement of at least one toward and from the other on said support, a pair of arms pivoted on said support and carry-

said blade whereby said blade engages and folds a sheet between said bars and the movement of said bars closer together forms a tight fold in said sheet and retains said sheet therebetween as said folding blade moves away from said bars.

3. A plastic sheet folding machine, comprising a support, a heated folding blade, a pair of fold forming bars mounted for movement of at least one toward and from the other on said support, a pair of arms pivoted on said support and carrying said folding blade for movement toward and from said bars in a direction substantially perpendicular to the plane of movement of said one bar, an operating lever mounted at one end on said support for oscillating movement, an actuating lever connected with said operating lever for oscillation thereby, a link connecting said actuating lever with one of said arms for moving said folding blade into cooperative sheet folding relation with said bars in movement of said operating and actuating levers in one direction and away from said bars in movement of said levers in the opposite direction, means operated by said actuating lever for moving said movable fold forming bar a limited distance toward said other bar when said actuating lever is moved in one direction to move said folding blade toward said bars to engage a sheet therebetween to cooperate in initially folding said sheet, said cam means moving said movable bar an additional distance toward said other bar in movement of said actuating member in said opposite direction for rightly folding said sheet between said bars while said folding blade is disengaged from the fold in said sheet and moved away from said bars.

4. A plastic sheet folding machine, comprising a support, a heated folding blade, a pair of fold forming bars mounted for movement of at least one toward and from the other on said support, a pair of arms pivoted on said support and carry-

11

ing said folding blade for movement toward and from said bars in a direction substantially perpendicular to the plane of movement of said one bar, an operating lever mounted at one end on said support for oscillating movement, an actuating lever connected with said operating lever for oscillation thereby, a link connecting said actuating lever with one of said arms for moving said folding blade into cooperative sheet folding relation with said bars in movement of said operating and actuating levers in one direction and away from said bars in movement of said levers in the opposite direction, cam means operated by said actuating lever for moving said movable fold forming bar a limited distance toward said other bar when said actuating lever is moved in one direction to move said folding blade toward said bars to engage a sheet therebetween for cooperation in initially folding said sheet, said cam means moving said movable bar an additional distance toward said other bar in movement of said actuating member in said opposite direction for tightly folding said sheet between said bars, and sheet engaging and holding means on the inner faces of said bars for retaining said sheet between said bars while said folding blade is withdrawn from the fold in said sheet and moved away from said bars.

5. A plastic sheet folding machine, comprising a support, a heated folding blade, a pair of fold forming bars mounted for movement of at least one toward and from the other on said support, a pair of arms pivoted on said support and carrying said folding blade for movement toward and from said bars in a direction substantially perpendicular to the plane of movement of said one bar, an operating lever mounted at one end on said support for oscillating movement, an actuating lever connected with said operating lever for oscillation thereby, a link connecting said actuating lever with one of said arms for moving said folding blade into cooperative sheet folding relation with said bars in movement of said operating and actuating levers in one direction and away from said bars in movement of said levers in the opposite direction, a carrier for said movable bar pivoted on said support, a cam rotatably mounted on said support, a cam follower on said carrier engaging said cam, and a double ratchet means for rotating said cam in one direction connected with said actuating arm for operation of said cam in both directions of movement, said cam being formed for operating said carrier to move said movable fold forming bar a limited distance toward said other bar when said actuating lever is moved in one direction to move said folding blade toward said bars for engaging and initially heating and folding a sheet between said bars about said blade, said cam being formed to move said bar an additional distance toward said other bar in movement of said actuating member in said opposite direction for tightly folding and cooling said sheet between said bars while said blade is withdrawn from the fold in said sheet.

6. A plastic sheet folding machine, comprising a supporting frame having a bar supporting ledge formed on the upper front edge thereof and having the lower frame portion extending forwardly in advance of said bar supporting ledge, a fold forming bar mounted on said ledge, a carrier having side extensions pivotally connected to said frame and a bar supporting ledge opposite the ledge on said frame, another fold forming bar mounted on the ledge of said carrier in opposed relation to the bar on said frame, said carrier co-

12

operating with said frame to provide an open discharge passage for folded sheets below said carrier in front of said frame, a heated folding blade, arms pivoted at the sides of said frame mounting said blade for movement to engage a marginal portion thereof between said bars for engaging and forcing a sheet therebetween to heat and form a fold in said sheet, and means for moving said folding blade and said carrier in timed relation relative to said frame carried fold forming bar for initially moving said carrier carried bar toward said frame carried bar a limited distance in forming said fold in said sheet, and said means moving said carrier carried bar closer to said frame carried bar in further operation to tightly form and cool the fold in said sheet while said blade is withdrawn from said fold.

7. A plastic sheet folding machine, comprising a supporting frame, a pair of arms pivoted on adjustable pivot members carried by said frame, a heated folding blade mounted on said arms, a pair of fold forming bars, one mounted on the front of said frame, a carrier pivoted on said frame mounting the other bar for movement toward and from the bar on said frame, means for moving said carrier on its pivot having complementary parts carried by said carrier and said moving means adjustable to vary the movement of said bar carried thereby relative to said bar on said frame to compensate for variations in the thickness of sheet material to be folded, said pivot members cooperating to adjust the position of said folding blade for centering said blade between said fold forming bars in sheet folding cooperation therebetween, and operating means for oscillating said folding blade toward and from a position with a margin thereof between said bars for heating and folding a sheet therebetween, and also operating said means for moving said carrier to move said bar thereon toward the other bar a limited initial distance for cooperation in folding a sheet about the margin of said folding blade when engaged therebetween, and said carrier moving said bar an additional amount toward said other bar responsive to said operating means for forming a tight fold in a sheet between said bars as said blade is moved away from said bars and disengaged from the fold in said sheet.

8. A plastic sheet folding machine comprising a pair of parallel fold forming bars, resilient sheet gripping members mounted on opposed faces of said bars, means mounting said bars for relative movement toward and from each other, a heated folding blade mounted for movement of a marginal portion thereof substantially perpendicular to the plane of movement of said bars and from a position between said bars, and operating means for moving said blade and said bars relative to each other in timed relation whereby said margin of said blade engages a sheet supported by said bars and folds said sheet between said bars while in spaced relation, said operating means moving said bars toward one another a limited distance in folding the sheet during engagement of said blade margin therebetween with the sheet engaged and retained between said gripping members, and said operating means moving said bars an additional distance toward one another to tightly engage said gripping members with the folded sheet for holding and tightly folding said sheet while said blade margin is withdrawn from said fold in the sheet.

9. A plastic sheet folding machine, comprising a pair of spaced parallel fold forming bars having longitudinal channels formed in the opposed

faces thereof, flexible gripper strips each having a margin secured in one side of one of the channels in said bars with the other margin projecting inwardly in spaced relation to the bottom of the channel to provide resilient sheet gripping portions on said bars, means mounting said bars for movement toward and from each other from spaced apart positions, a heated folding blade, means mounting said folding blade for movement in a direction substantially perpendicular to the plane of said bar movement toward and from a position where a margin of said folding blade projects between said bars and gripper strips, and operating means for moving said blade and bars in timed relation to fold a sheet by first engaging the margin of said blade with a sheet extending across said bars and folding said sheet between said bars in said position where said blade projects between said bars while said bars are moved toward one another for cooperation in folding said sheet about said blade margin; and secondly moving said bars an additional distance toward each other for engaging the inwardly projecting portions of said gripper strips with portions of said folded sheet at opposite sides of the fold formed therein for tightly folding said sheet after said blade margin is withdrawn from said fold.

10. A plastic sheet folding machine, comprising a rigid supporting frame having a flat sheet receiving top portion and side portions depending from the margins thereof, a carrier having a flat top portion in substantially coplanar relation to said flat top portion of said frame in edge-to-edge relation in front of said frame, said carrier having depending side extensions thereon pivotally mounted at the lower ends on the side portions of said frame for movement of said carrier toward and from said frame, a pair of fold forming bars each mounted on one of the opposed edges of said frame and carrier top portions in spaced parallel opposed relation and extending between the sides thereof, a heated folding blade in spaced parallel relation to said bars, means mounting said blade on said frame above the top portion for movement from a spaced position to and from a position where a margin of said blade extends between said bars, and operating means for said blade and carrier operable to move the blade to engage a sheet on said top portions over said bars and fold said sheet between said bars, said operating means initially moving said carrier to move the bar thereon a limited distance toward the other bar for cooperation with said blade in folding said sheet with said margin of said blade positioned between said bars, and said operating means moving said carrier an additional amount to move the bar thereon closer to the other bar for tightly gripping and folding said sheet after said operating means has withdrawn said blade margin from between said bars and the fold in said sheet.

11. A plastic sheet folding machine, comprising a rigid supporting frame having a flat sheet supporting top portion and side portions depending from the margins thereof, a carrier having a flat top portion in substantially coplanar relation to said flat top portion of said frame in edge-to-edge relation in front of said frame, said carrier having depending side extensions thereof pivotally mounted at the lower ends on the side portions of said frame for movement of the carrier top portion toward and from said frame top portion, a pair of fold forming bars each mounted on one of the opposed edges of said top portions of said car-

rier and frame and movable therewith in spaced parallel relation toward and from each other, a pair of arms each pivoted at one end on one of said frame side portions and having the opposite ends extending above said top portion at opposite sides thereof, a heated folding blade extending between and mounted on said opposite ends of said arms above said frame top portion for movement toward and from a position with a margin of said blade positioned between said bars, an operating shaft extending through said frame side portions and rotatably mounted therein, actuating levers mounted on the ends of said shaft adjacent the outer sides of said frame side portions, links connecting said actuating levers with said arms adjacent the outer sides of said frame side portions, means mounted on said frame side portions and operated by said actuating levers for moving said carrier in timed relation to said blade, and an operating lever mounted on said shaft between said side portions, extending laterally therefrom, and manually operable to move said blade and carrier for securing cooperation of said blade and pair of bars in forming a fold in a sheet placed on said top portions.

12. A plastic sheet folding machine, comprising a rigid supporting frame having a flat sheet supporting top portion, a carrier mounted for rocking movement on the front portion of said frame, and having a sheet supporting top portion in coplanar edge-to-edge relation with said top portion of said frame, a pair of fold forming bars each mounted in opposed relation on one of the opposed edges of said top portions, a pair of arms pivoted on said frame in spaced parallel relation, a heated folding blade mounted on said arms in spaced parallel relation above said forming bars and movable with said arms into folding cooperation with said bars, an operating shaft rotatable in and extending through said frame, actuating arms mounted on said shaft at opposite sides of said frame, links connecting respective actuating arms with adjacent arms, and an operating lever having one end rigidly secured to the central portion of said operating shaft and operable to move said blade and bars into cooperation for folding a sheet therebetween.

13. A plastic sheet folding machine, comprising a rigid supporting frame having a flat sheet supporting top portion, a carrier mounted on the front of said frame for rocking movement with portions in opposed relation to portions of said frame, a pair of forming bars mounted in opposed parallel relation on the opposed portions of said frame and carrier for relative movement toward and from each other, a pair of arms pivoted on said frame in spaced parallel relation having corresponding ends projecting above the frame, a folding blade mounted on and extending between said corresponding ends of said arms in parallel relation to said bars and movable with said arms toward and from folding cooperation with said bars, actuating levers mounted for rocking movement on said frame, means connecting said actuating levers with said pair of arms and said carrier to move said folding blade and carrier in securing a folding operation between said blade and said bars and means for changing the relation of said connecting means between said pair of arms and said carrier for varying the spaced relation of said folding blade and bars in folding cooperation.

14. A plastic sheet folding machine comprising a heated folding blade, a pair of relatively movable fold forming bars, means movably mount-

ing said bars and blade for movement into and out of fold forming cooperation, and operating means for moving said blade and bars in forming a fold in sheet material having a rotatable operating shaft, an operating lever mounted on and extending radially from said shaft, a rod projecting from said shaft in radial relation and laterally relative to said operating lever, a weight mounted on said rod for normally rotating said shaft in one direction to hold said operating lever in a starting position, and a dash pot for controlling the speed of rotation of said shaft by said weight, said operating lever being manually operable for rotating said shaft in an opposite direction, said operation of said shaft in opposite directions moving said blade and bars into and out of fold forming cooperation.

15. A plastic sheet folding machine, comprising a rigid supporting frame having a flat sheet supporting top portion, a pair of fold forming bars arranged in opposed spaced parallel relation, means mounting one of said bars on a marginal edge of said top portion, means mounting the other of said bars for movement toward and from said first-mentioned bar in aligned relation with and beyond said first mentioned bar and flat top portion, a folding blade having a narrow forming edge, means mounted on the sides of said frame mounting said folding blade above said bars in parallel spaced relation with said forming edge projecting toward said bars, an operating lever pivoted on said support at one end and having the opposite end depending therefrom, and means mounted on said frame below said flat top portion having operative connection with said folding blade and movable bar actuated by said operating lever in manual operation on said pivot for moving said folding blade to engage a sheet supported on said bars and flat top portion, fold it between said spaced bars and move said other bar toward said first bar in timed relation to said folding blade movement for folding cooperation to complete the formation of a folded sheet from a flat sheet.

16. A plastic sheet folding machine, comprising a supporting frame having a flat sheet supporting top portion, a pair of fold forming bars mounted on said frame, one bar being mounted on a marginal edge of said top portion, means mounting the other bar for movement toward and from the first-mentioned bar in substantially co-planar relation to said top portion, a folding blade mounted on said frame above said bars in edgewise relation for pivotal movement toward and from a position between said bars, an operating lever pivoted on said frame below said top portion, a laterally extending actuating arm connected with and pivotally moved by said

operating lever, a link connecting said arm with said folding blade for moving said blade in manual movement of said operating lever and means on said frame below said top portion operated by said operating lever for proportionately moving said movable fold forming bar toward said first-mentioned folding bar in timed relation to operation of said folding blade for folding a sheet supported on the top of said bars and top portion between said bars and said bars cooperating to hold and complete said fold in further proportionate movement of said one bar toward the other.

17. A plastic folding machine, comprising a supporting frame having a flat sheet supporting top portion, a pair of fold forming bars mounted in spaced parallel opposed relation along the front edge of said top portion, one of said bars being rigidly mounted along said marginal edge, means mounted on said frame below said top portion mounting the other bar for movement toward and from the first-mentioned bar, a folding blade, means mounting said folding blade in edgewise relation to said bars in spaced relation above said bars for movement toward and from a position with the lower edge between said bars for sheet folding cooperation therewith, said means being mounted on said frame below said top portion, an operating lever pivotally mounted at one end on said frame below said top portion with the free end in downwardly extending relation, actuating means carried by said frame below said top portion connected with said movable bar and operating lever for moving said movable bar a limited amount toward said other folding bar in initial operation of said operating lever, link means operatively connecting said operating lever with said blade mounting means for simultaneously moving said blade to engage and fold a sheet supported on said bars and top portion between said bars while said movable bar is moved said limited amount in said initial operation of said operating lever, and said actuating and link means being operated in further operation of said operating lever to move said movable bar toward said other bar an additional amount while said blade is moved from its position between said bars for completing the fold in said sheet.
